STRONG BOX

Harry D. Dwyer, 3326 Cherry Road, Anderson, Ind.

Filed Oct. 16, 1961, Ser. No. 67,095

Term of patent 14 years

(Cl. D58—12)

Fig. 1.

Fig. 2.

Fig. 3.

FIG. 1 is a front perspective view of a strong box, showing my new design.

FIG. 2 is a front perspective view of the strong box as it appears with the doors in open position.

FIG. 3 is a rear perspective view of the design as shown in FIG. 1.

I claim:

The ornamental design for a strong box, as shown.
